UNITED STATES PATENT OFFICE.

EDWARD A. FARR, OF MERIDEN, CONNECTICUT, ASSIGNOR TO MANNING, BOWMAN & COMPANY, OF MERIDEN, CONNECTICUT, A CORPORATION OF CONNECTICUT.

DESIGN FOR A PERCOLATOR COFFEE-POT.

43,244.

Specification for Design.

Patented Nov. 12, 1912.

Application filed June 13, 1912. Serial No. 703,567. Term of patent 7 years.

To all whom it may concern:

Be it known that I, EDWARD A. FARR, a citizen of the United States, residing at Meriden, New Haven county, Connecticut, have invented a new, original, and ornamental Design for a Percolator Coffee-Pot, of which the following is a specification, reference being had to the accompanying drawing, forming a part thereof, in which the

figure shown is a view in side elevation of the complete coffee-pot.

I claim:

The ornamental design for a percolator coffee pot, as shown.

EDWARD A. FARR.
